The ornamental design for a video recorder for vehicle, as shown and described.

DESCRIPTION

FIG. 1 is a perspective view of a video recorder for vehicle showing my new design;

FIG. 2 is a bottom view thereof;

FIG. 3 is a top view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken lines shown in the drawings represent portions of the video recorder for vehicle that form no part of the claimed invention.
